UNITED STATES PATENT OFFICE

164,445

REFRIGERATED BUTTER AND CREAM DISPENSING UNIT

Ronald R. Perkins, Dallas, Tex.

Application March 14, 1950, Serial No. 8,512

Term of patent 14 years

(Cl. D2—3)

To all whom it may concern:

Be it known that I, Ronald R. Perkins, a citizen of the United States of America, residing at Dallas, in the county of Dallas and State of Texas, have invented a new, original, and ornamental Design for a Refrigerated Butter and Cream Dispensing Unit, of which the following is a specification, reference being had to the accompanying drawing, forming a part thereof.

In the drawing:

Figure 1 is a front elevational view of a refrigerated butter and cream dispensing unit, showing my new design.

Figure 2 is a top plan view of the same.

Figure 3 is an end elevational view of the same showing the cream dispensing portion, and

Figure 4 is an end elevational view of the same showing the end opposite from Figure 3.

The back, not shown, is substantially plain.

I claim:

The ornamental design for a refrigerated butter and cream dispensing unit, as shown and described.

RONALD R. PERKINS.
